AIR-BRAKE AUTOMATIC BLEEDER-VALVE

Georges Emile Benoit, Ville St.-Pierre,
Quebec, Canada

Application February 14, 1948, Serial No. 8,367
In Canada May 26, 1947

3 Claims. (Cl. 303—70)

1

The present invention relates to a valve arrangement and, more particularly, an automatic bleeder valve used in connection with railway air brakes, which is provided with protection against bleeding the air reservoir of runaway cars.

In railway yards, among the many servicing operations required on the air brakes of railway cars, there is a bleeding of the individual car air reservoirs necessary before the cars or coaches can be shunted. This manual bleeding of air tanks, on each car, consumes a great amount of time and requires the almost exclusive services of several operators who could be otherwise employed elsewhere.

Again, in a system of air brakes provided with automatic bleeding means, it is necessary to ensure that a sudden and accidental uncoupling of the main air supply pipes, such as occurs, for example, in the case of runaway cars, will not cause automatic draining of the reservoirs of the uncoupled cars, and thus render their air brake system helpless.

The present invention has been conceived to decrease the amount of time and labour consumed by shunting operations, and to protect against accidental draining of a car's air system.

Consequently, the main object of the invention resides in the provision of means, provided in conjunction with railway air brake equipment, for automatically bleeding the auxiliary reservoirs of a train upon removing the pressure in the main air line prior to uncoupling.

Another object is the provision of automatic bleeding means of the character described, which contains means to protect the air brake system of a train from accidental debilitation or drainage.

Another object resides in the provision of means of the character described, which are applicable to existing equipment.

A still further object contemplates the provision of automatic air bleeding means of the character described operable only when a minimum brake pipe pressure has been reached.

Finally, still an important object relates to means of the character described, which would be simple, reliable in operation and relatively inexpensive.

Other objects and advantages of the invention will become apparent as the description progresses.

As an example, and for purposes of illustration only, a possible embodiment of the invention is shown in the annexed drawing, wherein:

2

Figure 1 is a perspective view of some elements of an air brake system with which the means of the invention are immediately associated.

Figure 2 is a sectional elevation of the invention when the system is in normal operation.

Figure 3 is a similar sectional elevation of the protective means of the invention when operative owing to accidental uncoupling.

Figure 4 is a perspective view of the valve disc, 10 and

Figure 5 is a plan of the valve seat against which the disc normally rests.

In the drawing, wherein similar reference characters represent corresponding parts throughout, a simplified and somewhat schematic showing (Figure 1) has been made to represent the essential elements of a freight car air brake system, and to illustrate the relation of the present valve means thereto. The air brake cylinder, then, is indicated by the letter A, this cylinder having a normal type three-way valve B associated with it and coupled in turn to the brake pipe C. This pipe C conducts the main supply of compressed air and is provided with an angle cock D at each end of the car, from which hose couplings E lead to adjoining cars. Each car is also provided with an auxiliary reservoir F, which is connected to and supplied by the valve B, by means of piping, thus enabling operation of the brake cylinder even when the main air supply is cut off.

For shunting operations, it is necessary to drain off the pressure from reservoir F in order to prevent locking of the brake by this pressure. The present invention, denoted generally by I, is secured to the auxiliary reservoir, and communicates with it as will be pointed out. The invention also is coupled by means of pipe 7 with the main brake pipe C, and the automatic bleeding means of the invention is adapted to operate when the air pressure in the main brake pipe falls below a predetermined amount.

Figure 2 shows the parts of the invention in detail. A box-like casing 8 encloses the whole, and the base plate of this frame is bolted to the reservoir through the gasket 9. In the drawing, the invention is shown secured to the top of reservoir F, but, as will be pointed out later, it will operate equally well when affixed underneath the reservoir.

Casing 8 encloses a chamber 10, at the ends of which are, respectively, the automatic bleeding means G and the protective means P. The air pressure in chamber 10, in normal operation, is the same as that of the reservoir F and the brake

pipe C, and this pressure is supplied from the latter through the protective means P.

Briefly, means P comprises a vertical cylindrically bored block integral with casing 8 and having interior-threaded ends. Similarly-threaded interchangeable fittings 11 and 12 having central bores are inserted at each end, and each of these bores is in turn threaded at its outer end. One of these fittings 11 is adjacent to the casing of reservoir F, and a plug 13 is screwed into this fitting. At the upper end of the block the coupling 14 from pipe 7 is screwed into fitting 12.

Between fittings 11 and 12, a disc valve 16 is slidable in the block, this valve consisting of the disc 17 mounted medially between the spiders 18 on the spider shaft 19 (see Figure 4). The spiders are guided by the interior bores of the fittings, and the disc is limited in its travel by a valve seat abutting from the inner end of each fitting. The seat 20 on fitting 12 has a continuous machined surface against which the disc may be tightly pressed. The seat 21 of fitting 11 (see Figure 5) has radial slots through which air may pass even when the disc rests against this valve seat.

Without considering further the operation of means P at present, it suffices to say that normally this valve provides communication between brake pipe C and chamber 10.

The automotive bleeding means C consists primarily of a pressure-operated piston valve. This valve is enclosed in a cylinder 25 which juts out into the chamber 10 and at the opposite end has a threaded flange 26 by which it is inserted into place in a horizontal bore through casing 8. A plug 27 is screwed into place outside flange 26 and holds the cylinder rigid.

At the end inside the chamber, the cylinder has an aperture 28, whilst at the flange end, an offset passage 29 in casing 8 couples the cylinder bore to a filter chamber 30, which is in turn open to the atmosphere through an axially bored plug 31. The purpose of the offset passage and filter chamber is to allow communication from the atmosphere to the flange end of the cylinder, whilst preventing the entrance of dirt therein.

Inside the chamber 10, the cylinder has a port 32 through its casing. From this port, a removably secured tube 33 communicates with the reservoir through apertures in the base plate of casing 8, the gasket, and the reservoir casing.

The piston 34, in the cylinder, has a spring 35 located between itself and the face of plug 27. Thus the piston is controlled by the pressure of the spring at one end, and the air pressure of chamber 10 at the other.

In operation, the air pressure existing in chamber 10 (and the brake pipe) acts behind the piston to push it towards the plug 27 thereby compressing spring 35 and shutting off port 32 and the communication between reservoir and passage 29 (see Figure 2). So long as a pressure exists in the brake pipe sufficient to so compress the spring, the valve will remain in the position shown in Figure 2 and air will remain stored in the auxiliary reservoir for automatic brake application as usual.

When, however, the pressure in the brake pipes is gradually reduced to a minimum all along the train the coiled spring will push the piston away from the plug 27, thereby opening the port 32 and allowing communication between the auxiliary reservoir and the passage to the atmosphere. Consequently the stored air is free to escape and the entire system is released, the brakes being rendered inoperative. This bleeder valve obvious-

ly performs automatically the function usually requiring a manual opening of drain cocks on each car reservoir.

However, whilst thus automatically bleeding a train system, the bleeder valve in itself defeats the entire purpose of the reservoir, which is to provide a store of compressed air to operate the brakes of a car despite the accidental uncoupling of air supply. Obviously some means must be added to prevent operation of the bleeder valve in such emergency cases, as opposed to the normal uncoupling of a system.

This function is performed by the protective means P, whose operation is clearly illustrated in Figures 2 and 3. Normally, when the brake pipe carries air under pressure, this air passes through pipe 7 and coupling 14 into the bore of fitting 12. The disc valve rests on the slotted valve seat 21 (see Figure 2) of fitting 11, owing to gravity, and the air passes through the slots into the bore of fitting 11 and against plug 13. The fitting 11 is further provided with a port 36 passing from its bore to a circumferential groove 37 in the threaded surface of the fitting. A vent 38, adjacent to this groove, pierces the wall of casing 8 holding means P, and opens into chamber 10.

Normally then, air may pass from the brake pipe C into chamber 10.

If, however, the pressure in the brake pipe drops rapidly owing to accidental uncoupling of the system, air will not pass from chamber 10 in the reverse direction to that described, since the disc valve 16 will, against the force of gravity, be lifted to rest against the smooth valve seat 20 (see Figure 3). Air will not pass the disc when it is so located, and the air pressure in chamber 10 will remain constant, thereby holding the bleeder valve in its inoperative position.

In the case where it is desired to release the air from the reservoirs, for example when uncoupling for shunting operations, the pressure in brake pipe C is not decreased so abruptly as in the case of an accidental uncoupling. Consequently the pressure differential operating on disc valve 16 is not sufficient to cause it to be lifted against valve seat 20. In such cases, then, air will pass out of chamber 10 in a reverse direction to that described, and the automatic bleeder valve will operate when the pressure in the chamber decreases below the critical value.

The critical pressure at which the bleeder valve operates, and the pressure differential required to operate the disc valve, may each be adjusted to the valve required for best operation in any system by varying the tension of spring 35 or the weight of disc 17.

A unique feature of the system resides in the provision for operation of the protective means even if it is required to secure the invention underneath the reservoir instead of on top as shown.

For this purpose, the small extension 40 is provided on the casing 8. This extension has a threaded bore of the same diameter of the bores of fittings 11 and 12, and either a plug similar to 13 or the pipe coupling 14 may be inserted into this extension. Normally this extension is plugged up.

When the invention is secured underneath the reservoir, however, the fittings 11 and 12 are interchanged and have plugs 13 inserted therein. The coupling 14 is inserted in extension 40 which is provided with a vent 41 leading through casing 8 into the main bore of means P. Fitting 12 has a circumferential groove 43 in its threaded surface which is adjacent to the opening of vent

41 when the fitting is in place. From this groove, a port 44 passes into the interior bore of fitting 12 and thus air may pass from the brake pipe into the protective means. As before, the air passes around the disc and through the slotted valve seat into fitting 11. From here the port 36 and circumferential groove 37 allow the air passage to the surface of the fitting, and a vent 45 piercing casing 8 at this point allows the air to enter chamber 10.

The operation of the protective means may therefore be equally well accomplished when the invention is secured to the bottom of the reservoir.

The casing 8 is further provided with manually operated cock 48 and removable access plate 49, neither of which is essential to operation.

The fittings 11 and 12 have suitably slotted outside ends to be engaged by a standard wrench, whilst all plugs and couplings are provided with hexagonal heads or other shapes suitable for easy removing.

The foregoing description shows clearly how the invention has been designed to perform automatically what normally constitutes a lengthy manual operation. Nevertheless, by the addition of protective means, such an automatic bleeding of air brake systems does not decrease the safety factor of the systems.

Although the present showing and description is especially adaptable to the Westinghouse air brake system, it is equally applicable to the newer so-called A-B system. In this last case, the valve of the present invention is inserted in the A-B valve line, whereby the said A-B valve will be bled instead of the reservoir, the result being the same within the particular arrangement of said A-B system.

It will be understood that the example of the invention described is to be taken as a preferred embodiment of same, and that various changes as to size, shape and arrangement of parts, or substitution of equivalents may be resorted to without departing from the spirit of the invention.

Having thus described my invention, I claim:

1. In an air brake system having an air-supplying brake pipe and air-storing auxiliary reservoir; in combination, a casing having an air-retaining chamber, a gravity-operated flow-responsive disc valve adapted to normally permit passage of air between said chamber and said brake pipe, whereby said disc valve suspends passage of air when a predetermined maximum outflow from the chamber is attained; and a pressure-responsive valve comprising a cylinder and piston, the cylinder having at each end a vent open to the atmosphere and to said chamber respectively and having at its side wall a port communicating with the reservoir, said piston slidable inside said cylinder to take a first position over said side port for closing the communication between said chamber

and said reservoir and a second position to open the port to said atmosphere vent when the air pressure in the chamber reaches a predetermined minimum value, said piston actuated solely upon pressure variations inside said chamber.

2. In an air brake system having an air-supplying brake pipe and air-storing auxiliary reservoir; in combination, a casing having an air-retaining chamber, a gravity-controlled flow-re-

10 sponsive disc valve having communication with said chamber and said brake pipe and adapted to normally permit passage of air, whereby said disc valve suspends passage of air when a predetermined maximum outflow from the chamber is attained, and a pressure responsive valve comprising a cylinder and piston, the cylinder having

15 at its side wall intermediate these vents terminal vents open respectively to the atmosphere and to said chamber and having a port communicat-

20 ing with the reservoir, a spring positioned in the cylinder between the atmospheric vent thereof and the piston and compressible by the latter, said piston slidable in the cylinder over said port and controlled solely by the chamber air pressure and by the spring pressure, whereby the piston opens the port to the atmosphere vent when the air pressure in said chamber reaches a predetermined minimum value.

3. In an air brake system having an air-supplying brake pipe and air-storing auxiliary reservoir, in combination, a casing having an air-retaining chamber, a pressure-responsive valve comprising cylinder and piston, said cylinder having

35 terminal vents open respectively to the atmosphere and to said chamber and having at its side wall intermediate said vents, a port communicating with the reservoir, said piston slidable over said port to open the same to said atmospheric vent when the chamber air pressure reaches a predetermined minimum value, and a gravity-operated flow-responsive disc valve having

40 communication with said brake pipe and the chamber whereby air normally passes therebetween, said disc valve movable vertically, inter-

45 changeable valve seats limiting disc movement, the lower valve seat having apertures whereby said disc valve closes against the smooth upper valve seat when a predetermined maximum air outflow from the chamber is attained, and said 50 disc valve having interchangeable means for coupling to the brake pipe at the top and bottom of the valve.

GEORGES EMILE BENOIT.
